UNITED STATES PATENT OFFICE

2,490,432

DROPPABLE FIGURE TARGET

James S. Guarino and Rocco M. Guarino,
Chicago, Ill.

Application September 28, 1948, Serial No. 51,544

5 Claims. (Cl. 273—102.1)

1

The present invention relates to target games. More particularly it relates to a game which may be played with missiles such as ping pong balls that are thrown at a target member and which has novel means for indicating a scoring hit.

An object of the invention is to provide a target game having a figure suspended on a cord and a target member in the form of a simple lever which may be set to clamp the cord and maintain the figure in elevated position, and which lever is operable by the impact of a missile to release the cord and allow the figure to drop, indicating a scoring hit.

Another object of the invention is to provide a new and improved game which is harmless and develops skill in playing and which incorporates means for providing additional amusement to players when a scoring hit is made on the target member of the game.

A further object of the invention is the provision of a new and improved game which is durable and extremely simple and inexpensive to construct but which nevertheless operates satisfactorily and does not have complicated mechanism which might get out of order frequently.

These and other objects, advantages and capabilities of the invention will become apparent from the following description wherein reference is had to the accompanying drawings, in which:

Fig. 1 is a front elevational view of the improved game of the present invention;

Fig. 2 is a top plan view of the game with the lever arm or target member shown in full lines in operative position and in phantom in inoperative position;

Fig. 3 is a vertical sectional view taken on the line 3—3 of Fig. 1;

Fig. 4 is a fragmentary vertical sectional view showing the position of the suspension cord and stop member when the figure is in its lowermost position; and

Fig. 5 is a vertical sectional view similar to Fig. 4 but showing the suspension cord and stop member in the position they assume when the figure is elevated.

Referring to the drawings and more particularly to Figs. 1, 2 and 3, it will be noted that the improved game of the present invention has a supporting frame including a generally rectangular base 10, a pair of upstanding standards 12 fixed to the base by means of brackets 14, a top member 16 supported upon the upper ends of the standards and a rear crosspiece 18 fixed to the upper ends of the standards immediately below the top member. These frame members are pref-

2

erably made of wood but any other lightweight material may be used.

As best seen in Figs. 2 and 5, the top member 16 is of generally semicircular shape in plan and has a substantially diametrically located aperture 20 forward of the rear crosspiece 18. A metal eyelet or grommet 22 may be secured in this aperture to present a nonfriction surface.

A figure 24 of any appropriate character and 10 of relatively lightweight material is suspended from the top member by means of a flexible cord 26 passing through the aperture 20, as best seen in Figs. 1 and 3. This cord is doubled and has its free ends secured to the figure while its doubled end has a stop means such as a bead 28 larger than the aperture 20 secured thereto. The cord is guided for movement below the top member by means of a pair of spaced eyes 30 screwed into the rear crosspiece 18, through each of which 15 an end of the cord passes. Preferably the length of the cord is such that when it is released and the figure is in its lowermost position, the latter will be suspended somewhat above the base 10. A recess 31 may be provided in the top member 16 in which the bead rests when the figure is in raised position, as shown in Figs. 4 and 5.

One of the features of the present invention is the improved mechanism which we have devised for clamping the cord to hold the figure in the elevated position shown in Fig. 1. This mechanism comprises a target member 32 including a lever arm 34 pivoted intermediate its ends as indicated in Figs. 1 and 2 to the lower side of the top member adjacent the outer edge of the latter by means of a cotter pin 36 or other suitable journaling means. The lever has an inwardly directed end 38 which extends to a point somewhat beyond the aperture 20 in the top member, while the other end of the lever projects laterally from the right side of the frame, as seen in Figs. 1 and 2, and carries a suitable target element 40 on its outer end, which element may be a metal or wood disc.

When the target member is in the position shown in full lines in Fig. 2, the cord 26 will be frictionally clamped between the rear crosspiece 18 and the inner end 38 of the lever, as indicated in Fig. 5. Since the figure 24 is of light weight, no other means is necessary to hold it in elevated position. However, if desired, the lever may be restrained slightly by making its journal 36 fairly tight so that the figure will not be accidentally released when it is suspended in elevated position but will be released only when the target element 40 is struck with sufficient force to pivot

the lever against the restraint offered by the journal in a direction to release the cord. Upon release of the cord the figure drops until the bead 28 engages the eyelet 22 in the top member. The figure is then suspended only a slight distance above the base 10.

In order to protect the figure when missiles are propelled at the target, a net 42 is provided on the forward side of the frame, which net is suspended from the top member in the manner best seen in Figs. 2 and 5. As there indicated the top member 16 is provided with a slot or groove 44 which extends substantially the length of the perimeter of the front side of this top member and with a plurality of radially extending slots 46 intersecting this peripheral slot. The peripheral slot 44 is adapted to receive the upper weft 48 of the net while the radially extending slots 46 receive the warp strands 50 of the net so that the net is suspended from the peripheral edge of the top member. The net is held taut by means of a wire hoop 52 conforming generally to the shape of the forwardly facing side of the top member. This hoop is fixedly secured at opposite ends to the upright standards 12 and the bottom end of the net is threaded upon this hoop.

Since the game will frequently be placed upon tables or like articles of furniture when it is being played, the underside of the base is preferably provided with feet 54 of rubber, felt, or other nonabrasive material.

From the above description of the construction of the improved game its operation should be apparent and, therefore, a detailed description thereof is not thought to be necessary. In setting the game for play, the bead 28 may be grasped to pull the cord 26 through the eyelet 22 for raising the figure 24 to its elevated position behind the net 42. The target member 32 is then pivoted to the full line position shown in Fig. 2 so that the cord is releasably clamped between the inner end 38 of the lever 34 and the rear crosspiece 18 thus holding the figure in its elevated position. Although it is intended that hand propelled projectiles such as ping pong balls or light rubber balls shall be used in playing the game, it will be apparent that toy guns shooting corks, or the like could also be used in playing the game. When the element 40 is struck with sufficient force to pivot the lever to the position shown in phantom in Fig. 2, the cord will be released and the figure will drop by gravity until the bead 28 engages the eyelet 22.

In order to provide additional amusement in playing the game, a receptacle 56 may be placed on the base in alignment with the aperture 20 in the top member so that the figure will drop into this receptacle when it is released. The receptacle is preferably partly filled with water, and in order to secure the same against being knocked over, the top side of the base is preferably provided with a recess 58 conforming in size to the bottom of the receptacle.

Having thus described our invention, what we claim as new and useful and desire to secure by Letters Patent of the United States is:

1. In a toy in combination a supporting frame including base and top members, a figure, a flexible cord for suspending said figure from said top member, and a rockably supported target member having a part adapted to cooperate with a portion of the frame frictionally to clamp said cord and hold the figure in an elevated position, said target member being rockable to another

position by the impact of a missile striking the same for releasing the cord to allow the figure to descend gravitationally.

2. In a toy in combination a supporting frame including a base supporting a top member having an aperture therein and a member forming an abutment on one side of said aperture, a figure, means for suspending said figure from said top member including a flexible cord passing through said aperture and having a stop at one end for limiting descent of said figure, a lever member pivoted intermediate its ends to said top to provide a part extending laterally of the frame and an opposite end portion on the same side of the abutment as the aperture adapted to clamp the cord against the abutment when the lever is at one position frictionally to clamp said cord and hold the figure in elevated position, said lever member being rockable to a second position for releasing said cord to allow the figure to descend, a target element on the laterally extending part of said lever for intercepting missiles propelled at it and thereby causing said lever to be pivoted to the last mentioned position, a protective screen protecting the figure from being struck by missiles, and a liquid receptacle adapted to be placed in vertical alignment with said figure into which the latter drops when said cord is released.

3. In a toy in combination a supporting frame including base and top members, a figure, a flexible cord for suspending said figure above said base, a rockable target member having a part adapted to cooperate with a portion of the frame frictionally to clamp said cord and hold the figure in a position elevated above said base when the said target member is in one position, said target member being rockable to another position by the impact of a missile striking the same for releasing the cord to allow the figure to descend gravitationally, and a protective screen secured to said frame for protecting the figure from being struck by missiles, said top member having a slot on its upper side substantially coextensive with the perimeter of its forwardly facing portions for receiving the top weft strand of said screen, and a plurality of vertical slots along the said forwardly facing portions for receiving the warp of said screen to support said screen, and means engaged with the screen adjacent its lower end for maintaining the same taut.

4. In a toy in combination, a supporting frame including a base supporting a top member having an aperture therein and a member forming an abutment on one side of said aperture, a figure, means for suspending said figure from said top member including a flexible cord passing through said aperture and having a stop at one end for limiting descent of said figure when the cord is free of restraint, a lever member pivoted intermediate its ends to said top to provide a part extending laterally of the frame and an opposite end portion on the same side of the abutment as the aperture adapted to clamp the cord against the abutment when the lever is at one position frictionally to clamp said cord and hold the figure in elevated position, said lever member being rockable to a second position for releasing said cord to allow the figure to descend, a target element on the laterally extending part of said lever for intercepting missiles propelled at it and thereby causing said lever to be pivoted to the last mentioned position, and a protective screen protecting the figure from being struck by missiles.

5. In a toy in combination, a supporting frame including a base supporting a top member hav-

ing an aperture therein and a member forming an abutment on one side of said aperture, a figure, means for suspending said figure from said top including a flexible cord passing through said aperture and having one end secured to said figure, means forming a stop of larger cross-sectional area than said aperture on the other end of said cord for engaging the top side of the aperture to fix the lower limit to which the figure on the cord may descend, said stop forming means being conformed to be readily grasped for manually raising said figure from its lower-most position, and a target member having a lever arm rockably secured intermediate its ends to said frame on the underside of said top to one side of said aperture and having one end portion extending beyond the other side of said aperture and disposed on the same side of said abutment as the aperture for frictionally clamping the cord against the abutment when the tar-

get member is at one position with sufficient force alone to sustain said figure at a raised position, and a target element on the opposite end of said lever arm disposed to one side of said frame at a position to be struck by missiles freely propelled at it, said target member being rockable by impact of the missile on said target element in a direction to release the cord and thus free the figure for descent gravitationally.
